STOP-MOTION FOR POWER-DRIVEN MACHINES.

1,243,609.

Specification of Letters Patent.

Patented Oct. 16, 1917.

Application filed April 14, 1917. Serial No. 162,550.

To all whom it may concern:

Be it known that we, LAWRENCE E. JOHNSON, a citizen of the United States of America, and a resident of Melrose, in the county 5 of Middlesex and Commonwealth of Massachusetts, and EDWARD ERICKSON, a subject of the Govt. of Russia, and a resident of Clifftondale, in the county of Essex and Commonwealth of Massachusetts, have invented certain new and useful Improvements 10 in Stop-Motions for Power-Driven Machines, of which the following is a specification.

This invention relates to stop motions for 15 power driven machines, and has for its object the provision of means whereby, without undue shock, the machine may be stopped always at substantially the same point.

The invention consists primarily in a cam 20 controlled pivoted lever for applying a brake shoe to the driving pulley at the same time the hub of said pulley is gripped by a coiled spring to prevent further rotation of said pulley.

25 The invention further consists in mechanism for actuating said controlling cam by means of a clutch rotated by the belt for rotating said driving pulley.

The invention consists further in certain 30 novel features of construction and arrangement of parts which will be fully understood by reference to the description of the drawings and to the claims hereinafter given.

For the purpose of illustrating the invention one preferred form thereof is illustrated 35 in the drawings, this form having been found to give satisfactory and reliable results, although it is to be understood that the various instrumentalities of which the invention 40 consists can be variously arranged and organized and that the invention is not limited to the precise arrangement and organization of these instrumentalities as herein shown and described.

45 In the drawings:

Figure 1 represents a vertical section on line 1—1 on Fig. 2 of a stop mechanism embodying the principles of the present invention.

50 Fig. 2 represents a vertical section of the same on line 2—2 on Fig. 1.

Fig. 3 represents a vertical section of the same on line 3—3 on Fig. 1.

Fig. 4 represents a horizontal section

through the frame and brake lever showing 55 in plan the various locking mechanisms and devices for releasing the same.

Fig. 5 represents a partial section on line 5—5 on Fig. 3.

Fig. 6 represents an elevation of a portion 60 of the clutch operating mechanism, and

Fig. 7 represents an elevation of a portion of the treadle controlled releasing mechanism.

Similar characters designate like parts 65 throughout the several figures of the drawings.

In the drawings, 10 is a portion of the frame of a machine having at its upper end a bearing 11 in which is mounted a revolvable shaft 12. The shaft 12 has secured to 70 one end a pulley 13 having a groove 14 in its periphery and provided with a cylindrical hub 15 having a chamber 16 therein.

The hub 15 extends into a chamber 17 in 75 a cylindrical member 18 loosely mounted on the shaft 12 between the bearing 11 and the inner end of the chamber 16 in the hub 15. The cylindrical member 18 is positioned within an annular flange 19 on said pulley 80 13, said flange having a peripheral groove 20 therein. The shaft 12 has also secured thereto a cam 21 or some similar operating member. Within the chamber 17 is positioned a coiled spring 22 normally in contact with the hub 15 and preventing the rotation of the pulley 13 independently of the member 18, one end of said spring 22 being secured at 23 to the flange 24 of said member 18, while the other end thereof projects 85 through a slot 25 in the end wall of said member 18, and is secured to an oscillating plate 26 mounted on an annular flange 27 formed upon the member 18. The plate 26 is provided with a toe 28 and a curved finger 29 the purposes of which will be herein-after described.

Beneath the pulley 13 is a sheave 30 having a peripheral groove 31 in which is one complete turn of the belt 32 which in its 100 movement rotates both the pulley 13 and said sheave 30 in the direction of the arrow *a* on Fig. 2.

The sheave 30 is mounted on a short shaft 33 and has a cone-shaped cavity with the 105 wall of which engages the cone clutch member 34 loosely mounted upon a sleeve 35 surrounding the shaft 33. The sleeve 35 is

secured in a projecting support 36 depending from the frame 10.

The cone clutch member 34 has formed integrally therewith a cam member 37 in 5 the eccentric path 38 of which is a truck 39 on an arm 40 pivoted at 41 to an ear 42 on the support 36. Between the cam member 37 and the support 36 is an antifriction member 43. The sleeve 35 is provided with 10 an annular flange 44 which is provided with a pin 45 to which one end of a flat spiral spring 46 is secured, the other end of which is secured to the pin 47 in the cone clutch member 34.

15 To the support 36 there is pivoted, at 48, a lever 49 which projects against a headed member 50 screwed into the end of the shaft 33.

The shank of the member 50 extends 20 through a washer 51 positioned against a shoulder in the sleeve 35, and said shank also extends through an anti-friction thrust bearing 52 between which and said washer 51 is a coiled spring 53 adapted to retain the 25 clutch members 30—34 in engagement. The lever 49 is provided with an arm 54 against the outer end of which bears the actuating rod 55 mounted in bearings 56 on the frame 10.

30 The upper end of the rod 55 has a semi-cylindrical projection 57 and a shoulder adapted to be engaged by a radial shoulder 58 on an oscillating member 59, mounted in a bearing in the frame 10 and having 35 clamped to one end an arm 60 to the outer end of which is pivoted a rod 61, the lower end of which is connected to any usual form of treadle (not shown).

The treadle is normally retained in raised 40 position by means of the spring 63 one end of which is secured to the frame 10. The member 59 is provided with a projecting lug 64 which during the oscillation of said member 59 is adapted to engage the toe 28 on plate 26 and move it in the direction of 45 the arrow *b* on Fig. 2, thereby expanding the spring 22 and releasing the grip thereof on the hub 15 of the pulley 13. The pulley 13 is then free to rotate the shaft 12 and the 50 cam member 21.

In the drawings the machine is shown with the various parts thereof in the position which they assume when the spring 22 is gripping the hub 15 of the pulley 13 to 55 prevent its rotation, and with the foot just removed from the treadle and said treadle raised by the spring 63 so that the lug 64 has returned to its normal position.

In the frame 10 adjacent to the oscillat- 60 ing member 59 is an oscillating pin 65 on the outer end of which is a crank arm 66 having a cam portion 67 coating with a cam projection 68 on the head 69 of the member 59 on which said projecting lug 64 65 is formed.

Pivoted at 70 to the outer end of the crank arm 66 is a bell crank lever 71 one arm of which has mounted on its outer end a roll 72 adapted to be engaged by the cam portion 73 on the periphery of the flange 19 during 70 the rotation of the pulley 13.

The other arm of the lever 71 is provided with a shouldered projection 74 adapted to engage the end 57 of the rod 55 and retain the clutch members 30—34 out of gripping 75 relation during the operation of the machine. A spring 76, one end of which is secured to the lever 71, retains the cam surface 67 in contact with the peripheral surface of the head 69.

When the foot is removed from the treadle and the spring 63 oscillates the member 59 to return the projecting lug 64 to its normal position, the cam 68 will operate against the cam face 67 on the crank arm 66 and move 85 said crank arm about the axis of its pivot 65 so that the roller 72 is in position to be struck by the cam portion 73 as the pulley 13 continues to rotate.

When this cam portion 73 comes into contact with the roller 72 the lever 71 will be moved about the axis of the pivot 70 and release the shouldered projection 74 from the end 57 of the rod 55 and permit this rod to be raised by the expansion of the spring 95 53 acting upon the member 49 provided with an arm 54 bearing against the lower end of said rod 55.

In the drawings, the shouldered projection 74 is shown in the position it assumes 100 when it has just been disengaged from the end 57 of the rod 55 and said rod 55 has been elevated. The expansion of the spring 53 to actuate the member 49 and raise the rod 55 at the same time moves the shaft 33 105 endwise and causes the clutch members 30 and 34 to be brought into engagement, thereby causing these two members to rotate together.

As the sheave 30 is being rotated when 110 brought into engagement with the clutch member 34, this rotation will be imparted to the cam 37 and cause it to be rotated in the direction of the arrow *c* on Fig. 3 of the drawings. This rotation of the cam mem- 115 ber 37 will cause the eccentric cam path 38 thereof to move the arm 40 outwardly about its pivot 41.

To the upper end of the arm 40 is pivoted 120 at 77 a link 78 the opposite end of which is pivotally connected to a plunger 79 adapted to reciprocate in a chamber 80 of a dashpot 81 formed upon the lower end of a brake arm 82 pivoted at 83 to the frame 10. The plunger 79 has a passage 82 extending axially therethrough, which passage is adapted to be closed by a flexible valve member 83 when said plunger 79 is moved to the inner end of the chamber 80.

This valve member 83 is provided with an 130

opening 84 therethrough offset from the passage 82. As the plunger 79 moves outwardly in the chamber 80 the valve member 83 is adapted to be slightly cupped, thereby 5 permitting the air to enter through the passage 82 and through the opening 84 into the chamber 80. The inner end of the chamber 80 is provided with a needle valve 85 having a passage 86 therethrough.

10 This valve 85 may be nicely adjusted to regulate the escape of air from the chamber 80 during the inward movement of the plunger 79. To the upper end of the brake lever 82 is pivoted at 87 a friction block 15 88 which fits into the V groove 20 in the annular flange 19 of the pulley 13. The purpose of this friction block 88 is to engage the walls of the V groove and retard the rotation of the pulley 13 and reduce its speed 20 to a minimum before the coiled spring 22 is permitted to grip the hub 15 of the pulley 13 to arrest its further movement.

When the pulley 13 is rotated at a high rate of speed, it is necessary to apply greater 25 friction of the friction pad 88 to retard its movement than would be the case when the pulley was rotating at a slower speed. This is accomplished automatically by means of the needle valve 85 which permits the escape 30 from the chamber 80 of a less amount of air through the passage 86 when the pulley is rotating at a high rate of speed than is permitted to escape when the pulley is permitted to rotate at a slow speed.

35 On the pivot 87 is a tripping lever 89 having a projecting end 90 engaging the curved finger 29 on the plate 26. The other arm of the lever 89 is provided with a roll 91 in the path of the cam portion 92 on the periphery of the annular flange 19. When the brake shoe 88 is moved into frictional contact with the walls of the V groove 20 the pivot 87 will be moved inwardly and with the shoulders 29—90 as a fulcrum the roller 40 91 will be moved inwardly toward the axis of the shaft 12 into the path of the cam portion 92.

In the rotation of the pulley 13 this cam portion 92 will contact with the roller 91 50 and move the lever 89 about the axis of the pivot 97 and disengage the shoulder 90 from the finger 29, thereby unlocking the plate 26, thus permitting the spring 22 to return to its normal position in contact with the periphery of the flange 15. This gripping 55 contact of the spring with the hub 15 will prevent further rotation of the pulley 13.

The brake lever 82 is provided with an inwardly extending arm 93 which has a laterally extending lug 94 adapted to contact with a lug 95 on the frame 10 to limit 60 the outward movement of the brake shoe 88. In the forward end of the arm 93 is mounted a rod 96 the upper end of which is pivoted 65 at 97 to the cylindrical member 18, thereby

regulating the movement of said member 18 about the axis of the shaft 12. This member 18 is provided with a lug 98 which is adapted to contact with a portion of the frame 10 and remain in contact therewith 70 when the stop mechanism has been fully arrested.

The rod 96 is threaded at 99 and has adjustably mounted thereon a nut 100 against the upper end of which rests a washer 101 75 within the chamber 102 and in the upper portion of the arm 93. Between a shoulder 103 on the rod 96 and said washer 101 is interposed a strong coiled spring 104. Normally the washer 101 is slightly removed 80 from the inner end of the chamber 102 as indicated in Fig. 3 of the drawings. The lower portion of the arm 93 is also provided with a chamber 105 in which is positioned a lighter spring 106, the inner end of which 85 bears against the inner end of said chamber.

The outer end of the spring 106 bears against a nut 107 adjustably mounted upon the lower end of the rod 96. When the shoulder 90 on the tripping lever 89 is released 90 from the finger 29 the cylindrical member 18 will be moved in the direction of the arrow d on Fig. 3 of the drawings by the momentum of the rotating pulley 13. In this rotation the rod 96 will be 95 moved downwardly until the washer 101 comes into contact with the inner wall of the chamber 102, thereby compressing the spring 104. At this time the stop lug 93 is moved slightly away from the frame 10. 100

At the same time that the spring 104 is compressed additional friction is applied to the pulley 13 to stop the momentum thereof, and when the speed has been retarded sufficiently the spring 104 will again expand 105 to move the rod 96 upwardly and rotate the cylindrical member 18 in the opposite direction until the lug 98 comes into contact with the frame.

In order to provide a means whereby additional friction may be applied to the pulley 13 when desired without necessitating further expansion of the main gripping spring 22, the construction of connection between the rod 96 and the forward end 110 of the arm 93 is provided. It is obvious that when the forward end of the arm 93 is moved upwardly the upper end of the brake lever 82 with the shoe 88 pivoted thereto will be moved outwardly and release the frictional contact upon the pulley 13. This is objectionable as it is desired to provide some means whereby the friction upon the pulley will be continued even when the stop lug 98 is in contact with the 115 frame 10.

It is obvious that when the lug 98 is in contact with the frame further movement of the rod 96 is prevented. When the brake arm 82 is moved about its pivot 83 to ap- 130

ply more pressure to the pulley 13, the forward end of the arm 93 is moved downwardly compressing the spring 106 without effecting any movement of the rod 96.

5 The outward movement of the lever 89 is limited by the stop member 108 and the said lever 89 is normally retained in contact with said stop member 108 by means of the spring 109 positioned in the lug 110 on the 10 brake lever 82.

In the normal position of the cam 37 the roll 39 on the end of the lever 40 is in contact with the inner end of the eccentric cam groove 38 and when the cam member 37 has 15 been rotated about the axis of the shaft 33 to move the plunger 79 inwardly into the chamber 80, thereby causing the operation of the braking lever 82 and stopping the rotation of the pulley 13, the spring 46 is 20 simultaneously wound up.

As soon in the operation of the stop mechanism the clutch members 30 and 34 are separated, the clutch member 34 is free to be moved about the sleeve 35 and at this 25 time the spring 46 will uncoil and return the cam member 37 to its normal position with the roller 39 at the inner end of the cam groove 38, as shown in Fig. 3 of the drawings.

30 It is believed that the operation and many advantages of this invention will be fully understood from the foregoing description.

Having thus described our invention, we claim:

35 1. In a device of the class described, the combination of a driving shaft; a pulley secured thereto having a hub; a disk on said shaft having an annular flange surrounding said hub; a spring interposed between 40 said flange and said hub and normally engaging the periphery of said hub, one end of said spring projecting through a slot in said disk while the other end is secured to said flange; and means coacting with the 45 projecting end of said spring for releasing the spring from contact with said hub.

2. In a device of the class described, the combination of a driving shaft; a pulley secured thereto having a hub; a disk on said 50 shaft having an annular flange surrounding said hub; a spring interposed between said flange and said hub and normally engaging the periphery of said hub, one end of said spring projecting through a slot in said 55 disk while the other end is secured to said flange; a plate loosely mounted on said shaft and to which the projecting end of said spring is secured; and means for moving said plate about the axis of said shaft there- 60 by releasing the spring from contact with said hub.

3. In a device of the class described, the combination of a driving shaft; a pulley secured thereto having a hub; a disk on

65 said shaft having an annular flange surrounding said hub; a spring interposed between said flange and said hub and normally engaging the periphery of said hub, one end of said spring projecting through a slot in said disk while the other end is secured to said flange; a plate loosely mounted on said shaft and to which the projecting end of said spring is secured, said plate having a projecting toe; and a pivoted member 70 adapted to be moved into contact with said toe, thereby moving said plate about the axis of said shaft and releasing the spring from contact with said hub.

4. In a device of the class described, the combination of a driving shaft; a pulley secured thereto having a hub; a disk on said shaft having an annular flange surrounding said hub; a spring interposed between said flange and said hub and normally engaging 75 the periphery of said hub, one end of said spring projecting through a slot in said disk while the other end is secured to said flange; a plate loosely mounted on said shaft and to which the projecting end of said spring is secured, said plate having a projecting toe; and a treadle actuated pivoted member 80 adapted to be moved into contact with said toe, thereby moving said plate about the axis of said shaft and releasing the spring from contact with said hub.

5. In a device of the class described, the combination of a driving shaft; a pulley secured thereto having a hub; a disk on said shaft having an annular flange surrounding said hub; a spring interposed between said 85 flange and said hub and normally engaging the periphery of said hub, one end of said spring projecting through a slot in said disk while the other end is secured to said flange; a plate loosely mounted on said shaft and to which the projecting end of said spring is secured, said plate having a projecting toe; and a treadle actuated pivoted member 90 adapted to be moved into contact with said toe, thereby moving said plate about the axis of said shaft and releasing the spring from contact with said hub.

5. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other end is secured to said flange; a plate loosely mounted on said shaft and to which the projecting end of said spring is secured, said plate having a shouldered finger; means for moving said plate about the axis of said shaft to release the spring from contact with said hub; and a member 100 coacting with said shouldered finger to lock said plate from reverse movement.

6. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other end is secured to said flange; a plate loosely mounted on said shaft and to which the projecting end of said spring is secured, said plate having a shouldered finger, means for moving said plate about the axis of said shaft to release the spring from contact with said hub; a member coacting with said shouldered finger 105 110 115 120 125

to lock said plate from reverse movement; and means for releasing said locking member.

7. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other end is secured to said flange; a plate loosely mounted on said shaft and to which the projecting end of said spring is secured, said plate having a shouldered finger; means for moving said plate about the axis of said shaft to release the spring from contact with said hub; a member coacting with said shouldered finger to lock said plate for reverse movement; and means rotatable with said pulley for releasing said locking member.

8. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other end is secured to said flange; a plate loosely mounted on said shaft and to which the projecting end of said spring is secured, said plate having a shouldered finger; means for moving said plate about the axis of said shaft to release the spring from contact with said hub; a pivoted member coacting with said shouldered finger to lock said plate from reverse movement and provided with an operating arm; and a cam rotatable with said pulley for engaging said arm and releasing said member from engagement with said finger.

9. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other end is secured to said flange; a pivoted brake lever; a shoe thereon adapted to engage said pulley; a two armed lever pivoted to said brake lever with one arm provided with a hooked projection; an oscillating plate to which is secured the projecting end of said spring, said plate having a hooked finger adapted to engage said hooked projection; a cam rotatable with said pulley; a roll on the other arm of said two armed lever; and means for moving said brake lever about its pivot to bring said roll in the path of said cam.

10. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other end is secured to said flange; a pivoted brake lever; a shoe thereon adapted to engage said pulley; a two armed lever pivoted to said brake lever with one arm provided with a hooked projection; an oscillating plate to which is secured the projecting end of said spring, said plate having a hooked finger adapted to engage said hooked projection; a cam rotatable with said pulley; a roll on the other arm of said two armed lever; means for moving said brake lever about its pivot to bring said roll in the path of said cam; a stop to limit the outward movement of the hooked projection; and means for forcing said projection toward said stop.

11. In a device of the class described, the combination of a driving shaft; a pulley secured thereto having a hub; a disk on said shaft having an annular flange surrounding said hub; a helical spring between said hub and flange and normally in gripping contact with said hub, one end of said spring being secured to said flange and the other end projecting through a slot in said disk; an oscillating member to which said projecting end of said spring is secured; means under the control of the operator for moving said oscillating member in one direction to expand said spring; and means coacting with said oscillating member for locking said member with the spring expanded.

12. In a device of the class described, the combination of a driving shaft; a pulley secured thereto having a hub; a disk on said shaft having an annular flange surrounding said hub; a helical spring between said hub and flange and normally in gripping contact with said hub, one end of said spring being secured to said flange and the other end projecting through a slot in said disk; an oscillating member to which said projecting end of said spring is secured; means under the control of the operator for moving said oscillating member in one direction to expand said spring; means coacting with said oscillating member for locking said member with the spring expanded; and means rotatable with said pulley for releasing said locking means.

13. In a device of the class described, the combination of a driving shaft; a pulley secured thereto having a hub; a disk on said shaft having an annular flange surrounding said hub and a stop lug on said disk nor-

- 6 mally contacting with a fixed part of the frame; a helical spring between said hub and flange and normally in gripping contact with said hub, one end of said spring being secured to said flange and the other end projecting through a slot in said disk; an oscillating member to which said projecting end of said spring is secured; means under the control of the operator for moving 10 said oscillating member in one direction to expand said spring; and means coacting with said oscillating member for locking said member with the spring expanded.
14. In a device of the class described, the 15 combination of a driving shaft; a pulley secured thereto; a member loosely mounted to oscillate on said shaft; a device interposed between said member and pulley for normally preventing the rotation of said pulley 20 independently of said member; means for releasing said device from said pulley to permit its rotation; a pivoted lever; a pulley engaging brake shoe carried by said lever; and a cam for controlling the movement of said lever about its pivot.
15. In a device of the class described, the 30 combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; and an eccentric cam for controlling the movement of said lever about its pivot.
16. In a device of the class described, the 40 combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; a pivoted arm; a link be- 45 tween said arm and lever; and a cam for controlling the movement of said lever about its pivot.
17. In a device of the class described, the 50 combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; a pivoted arm; a link be- 55 tween said arm and lever; and a cam for controlling the movement of said lever about its pivot.

its pivot; means rotatable with said pulley for moving said cam in one direction; and a spring for returning it to its normal position.

18. In a device of the class described, the 70 combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; a pivoted arm; a roller in the end thereof; a link between said lever and arm; and an oscillating disk having an eccentric cam path in which said roller is positioned.

19. In a device of the class described, the 85 combination of a driving shaft; a pulley secured thereto; a member loosely mounted to oscillate on said shaft; a device interposed between said member and pulley for normally preventing the rotation of said 90 pulley independently of said member; means for releasing said device from said pulley to permit its rotation; a pivoted lever; a pulley engaging brake shoe carried by said lever; a dash pot on said lever; a 95 plunger therein; and cam mechanism for controlling the inward movement of said plunger.

20. In a device of the class described, the 100 combination of a driving shaft; a pulley secured thereto; a member loosely mounted to oscillate on said shaft; a device interposed between said member and pulley for normally preventing the rotation of said pulley independently of said member; 105 means for releasing said device from said pulley to permit its rotation; a pivoted lever; a pulley engaging brake shoe carried by said lever; a dash pot on said lever; a plunger therein; a pivoted arm; a link be- 110 tween said arm and plunger; a roll on the end of said arm; and a revolvable disk with an eccentric cam path in which said roll is positioned.

21. In a device of the class described, the 115 combination of a driving shaft; a pulley secured thereto; a member loosely mounted to oscillate on said shaft; a device interposed between said member and pulley for normally preventing the rotation of said 120 pulley independently of said member; means for releasing said device from said pulley to permit its rotation; a pivoted lever; a pulley engaging brake shoe carried by said lever; an arm on said lever; a rod 125 yieldingly mounted in said arm and connected at its opposite end with said oscillating member; and a cam controlling the movement of said lever about its pivot.

22. In a device of the class described, the 130

- combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; an arm on said lever having alined shouldered cavities in opposite sides thereof connected by an opening of less diameter; a shouldered rod connected at one end to said oscillating member and having at the opposite end a reduced shank extending through said opening; a nut on the outer end of said shank; a spring between the shoulder on said rod and the bottom of one cavity; a lighter spring between said nut and the bottom of the other cavity; a lug on said oscillating member limiting its movement in one direction; and a cam controlling the movement of said lever about its pivot.
23. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; an arm on said lever having alined shouldered cavities in opposite sides thereof connected by an opening of less diameter; a shouldered rod connected at one end to said oscillating member and having at the opposite end a reduced threaded shank extending through said opening; an adjustable sleeve on said threaded shank; a nut on the outer end of said shank; a spring between the shoulder on said rod and the bottom of one cavity; a washer between said spring and the end of said sleeve; a lighter spring between said nut and the bottom of the other cavity; a lug on said oscillating member limiting its movement in one direction; and a cam controlling the movement of said lever about its pivot.
24. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; an arm on said lever; a rod yieldingly mounted in said arm and connected at its opposite end with said oscillating member; and means controlling the movement of said lever about its pivot.
25. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; an arm on said lever having alined shouldered cavities in opposite sides thereof connected by an opening of less diameter; a shouldered rod connected at one end to said oscillating member and having at the opposite end a reduced shank extending through said opening; a nut on the outer end of said shank; a spring between the shoulder on said rod and the bottom of one cavity; a lighter spring between said nut and the bottom of the other cavity; a lug on said oscillating member limiting its movement in one direction; and means controlling the movement of said lever about its pivot.
26. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; an arm on said lever having alined shouldered cavities in opposite sides thereof connected by an opening of less diameter; a shouldered rod connected at one end to said oscillating member and having at the opposite end a reduced threaded shank extending through said opening; an adjustable sleeve on said threaded shank; a nut on the outer end of said shank; a spring between the shoulder on said rod and the bottom of one cavity; a washer between said spring and the end of said sleeve; a lighter spring between said nut and the bottom of the other cavity; a lug on said oscillating member limiting its movement in one direction; and means controlling the movement of said lever about its pivot.
27. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; and revoluble means for controlling the movement of said lever about its pivot.
28. In a device of the class described, the

combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; a pivoted arm; a link between said arm and lever; and means coacting with said link for controlling the movement of said lever about its pivot.

29. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; a pivoted arm; a link between said arm and lever; a cam for controlling the movement of said lever about its pivot; means rotatable with said pulley for moving said cam in one direction; a spring for returning it to its normal position; and means revoluble with said pulley for actuating said cam.

30. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; a pivoted arm; a roller in the end thereof; a link between said lever and arm; an oscillating disk having an eccentric cam path in which said roller is positioned; and means revoluble with said pulley for actuating said cam.

31. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; a dash pot on said lever; a plunger therein; cam mechanism for controlling the inward movement of said plunger; and means revoluble with said pulley for actuating said cam.

32. In a device of the class described, the combination of a driving shaft; a pulley secured thereto; a member loosely mounted to oscillate on said shaft; a device interposed

between said member and pulley for normally preventing the rotation of said pulley independently of said member; means for releasing said device from said pulley to permit its rotation; a pivoted lever; a pulley engaging brake shoe carried by said lever; a dash pot on said lever; a plunger therein; a pivoted arm; a link between said arm and plunger; a roll on the end of said arm; a revoluble disk with an eccentric cam path in which said roll is positioned; and means revoluble with said pulley for rotating said disk.

33. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a pivoted lever; a pulley engaging brake shoe carried by said lever; and means for controlling the movement of said lever about its pivot.

34. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other end is secured to said flange; a brake mechanism for said pulley; and means coacting with the projecting end of said spring for releasing the spring from contact with said hub, and simultaneously releasing said brake mechanism from said pulley.

35. In a device of the class described, the combination of a driving shaft; a pulley secured thereto having a hub; a disk on said shaft having an annular flange surrounding said hub; a spring interposed between said flange and said hub and normally engaging the periphery of said hub, one end of said spring projecting through a slot in said disk while the other is secured to said flange; a plate loosely mounted on said shaft and to which the projecting end of said spring is secured; a brake shoe normally in contact with said pulley; and means for moving said plate about the axis of said shaft thereby releasing the spring from contact with said hub and simultaneously releasing said shoe from contact with said pulley.

36. In a device of the class described, the combination of a driving shaft; a pulley secured thereto having a hub provided with a peripheral groove; a disk on said shaft having an annular flange surrounding said hub; a spring interposed between said flange and said hub and normally engaging

the periphery of said hub, one end of said spring projecting through a slot in said disk while the other end is secured to said flange; a plate loosely mounted on said shaft and to which the projecting end of said spring is secured, said plate having a projecting toe; a brake shoe normally in contact with the walls of said groove; and a pivotal member adapted to be moved into contact 10 with said toe, thereby moving said plate about the axis of said shaft and releasing the spring from contact with said hub.

37. In a device of the class described, the combination of a driving shaft; a pulley secured thereto having a hub; a disk on said shaft having an annular flange surrounding said hub; a spring interposed between said flange and said hub and normally engaging the periphery of said hub, one end of said 20 spring projecting through a slot in said disk while the other end is secured to said flange; a plate loosely mounted on said shaft and to which the projecting end of said spring is secured, said plate having a projecting toe; a pivotal member adapted to be moved into contact with said toe, thereby moving said plate about the axis of said shaft and releasing the spring from contact with said hub; and means under the control of the operator for actuating said pivotal member.

38. In a device of the class described, the combination of a driving shaft; a pulley secured thereto having a hub; a disk on said shaft having an annular flange surrounding said hub; a spring interposed between said flange and said hub and normally engaging the periphery of said hub, one end of said 35 spring projecting through a slot in said disk while the other end is secured to said flange; a plate loosely mounted on said shaft and to which the projecting end of said spring is secured, said plate having a shouldered finger; means under the control of the operator for moving said plate about 40 the axis of said shaft to release the spring from contact with said hub; and a member coacting with said shouldered finger to lock said plate from reverse movement.

39. In a device of the class described, the combination of a driving shaft; a pulley secured thereto having a hub and provided with a peripheral cam projection; a disk on said shaft having an annular flange surrounding said hub; a spring interposed between said flange and said hub and normally engaging the periphery of said hub, one end of said spring projecting through a slot in said disk while the other end is secured to said flange; a plate loosely mounted 55 on said shaft and to which the projecting end of said spring is secured, said plate having a shouldered finger; means under the control of the operator for moving said plate about the axis of said shaft to release the spring from contact with said hub; a 60 plate

pivoted member coacting with said shouldered finger to lock said plate from reverse movement and provided with an arm adapted to be engaged by said cam projection; and means for moving inwardly the 70 pivot of said locking member to cause the arm of said lever to be moved into the path of said cam projection to be engaged thereby in the rotation of the pulley whereby the pivoted member will be moved about its 75 pivot and disengage said locking member from said shouldered finger.

40. In a device of the class described, the combination of a driving shaft; a pulley secured thereto having a hub and provided with a peripheral cam projection; a disk on said shaft having an annular flange surrounding said hub; a spring interposed between said flange and said hub and normally engaging the periphery of said hub, 85 one end of said spring projecting through a slot in said disk while the other end is secured to said flange; a plate loosely mounted on said shaft and to which the projecting end of said spring is secured, 90 said plate having a shouldered finger; means for moving said plate about the axis of said shaft to release the spring from contact with said hub; a member coacting with said shouldered finger to lock said plate 95 from reverse movement and normally out of the path of said cam projection; and means for moving said member into position to be engaged by said cam projection whereby said locking member may be released from engagement with said shouldered finger during the rotation of said 100 pulley.

41. In a device of the class described, the combination of a driving shaft; a pulley secured thereto having a hub and provided with a peripheral cam projection; a disk on said shaft having an annular flange surrounding said hub; a spring interposed between said flange and said hub and normally 110 engaging the periphery of said hub, one end of said spring being secured to said flange; a plate loosely mounted on said shaft and to which the other end of said spring is secured, said plate having a shouldered finger; 115 means for moving said plate about the axis of said shaft to release the spring from contact with said hub; a pivoted member coacting with said shouldered finger to lock said plate from reverse movement and provided with an operating arm out of the path of said cam projection when said member and finger are engaged; and means for moving said arm into the path of said projection whereby said arm may be moved about 120 its pivot and said member released from engagement with said finger.

42. In a device of the class described, the combination of a driving shaft; a pulley secured thereto having a hub; a disk on said 130

- shaft having an annular flange surrounding said hub; a spring interposed between said flange and said hub and normally engaging the periphery of said hub, one end of said 5 spring projecting beyond said disk while the other end is secured to said flange; a pivoted brake lever; a shoe thereon adapted to engage said pulley; a two armed lever pivoted to said brake lever with one arm provided with a hooked projection; an oscillating plate to which is secured the projecting end of said spring, said plate having a hooked finger adapted to engage said hooked 10 projection; a cam rotatable with said pulley; a roll on the other arm of said two armed lever; means for moving said brake lever about its pivot to bring said roll into the path of said cam; and yielding means 15 for moving said brake lever about its pivot.
43. In a device of the class described, the combination of a driving shaft; a pulley secured thereto having a hub; a disk on said shaft having an annular flange surrounding said hub; a spring interposed between said 20 flange and said hub and normally engaging the periphery of said hub, one end of said spring projecting through a slot in said disk while the other end is secured to said flange; a pivoted brake lever; a shoe thereon adapted 25 to engage said pulley; a two armed lever pivoted to said brake lever with one arm provided with a hooked projection; an oscillating plate to which is secured the projecting end of said spring, said plate having a hooked finger adapted to engage said hooked 30 projection; a cam rotatable with said pulley; a roll on the other arm of said two armed lever; means for moving said brake lever about its pivot to bring said roll 35 into the path of said cam; a stop to limit the outward movement of the hooked projection; means for forcing said projection toward said stop; and yielding means for moving said brake lever about its pivot.
44. In a device of the class described, the combination of a driving shaft; a pulley secured thereto having a hub; a disk on said shaft having an annular flange surrounding said hub; a helical spring between said hub 40 and flange and normally in gripping contact with said hub, one end of said spring being secured to said flange and the other end projecting beyond said disk; an oscillating member to which said projecting end of said spring is secured; means under the control of the operator for moving said oscillating member in one direction to expand said spring; mechanism coacting with said oscillating member for locking said member with the spring expanded; and means for 45 releasing said locking mechanism at a predetermined point in the rotation of said pulley.
45. In a device of the class described, the combination of a driving shaft; a pulley se- 50 cured thereto having a hub; a disk on said shaft having an annular flange surrounding said hub; a helical spring between said hub and flange and normally in gripping contact with said hub, one end of said spring being secured to said flange and the other end projecting beyond said disk; an oscillating member to which said projecting end of said spring is secured; a pivoted lug for moving said oscillating member in one direction to 55 expand said spring; means under the control of the operator for moving said lug; means coacting with said oscillating member for locking said member with the spring expanded; and means rotatable with said pulley for releasing said locking means.
46. In a device of the class described, the combination of a driving shaft; a pulley secured thereto having a hub; a disk on said shaft having an annular flange surrounding said hub and a stop lug on said disk normally contacting with a fixed part of the frame; a helical spring between said hub and flange and normally in gripping contact with said hub, one end of said spring being secured to said flange and the other end projecting beyond said disk; an oscillating member to which said projecting end of said spring is secured; a pivoted lug for moving said oscillating member in one direction to 60 expand said spring; means under the control of the operator for moving said lug; means coacting with said oscillating member for locking said member with the spring expanded; means rotatable with said pulley for releasing said locking means; and mechanism for locking said pivoted lug at the completion of its operative movement.
47. In a device of the class described, the combination of a driving shaft; a pulley secured thereto; a member loosely mounted to oscillate on said shaft; a device interposed between said member and pulley for normally preventing the rotation of said pulley independently of said member; means for 65 releasing said device from said pulley to permit its rotation; a pivoted lug for actuating said releasing means; and a member under the control of the operator for moving said pivoted lug about its pivot.
48. In a device of the class described, the combination of a driving shaft; a pulley secured thereto having a cam projection revoluble therewith; a member loosely mounted to oscillate on said shaft; a device interposed between said member and pulley for normally preventing the rotation of said pulley independently of said member; means for releasing said device from said pulley to permit its rotation; a pivoted lug for actuating said releasing means provided with a peripheral cam; a member under the control of the operator for moving said pivoted lug about its pivot; a pivoted arm having a cam surface normally retained in con- 70 75 80 85 90 95 100 105 110 115 120 125 130

tact with said peripheral cam; a two armed lever pivoted to the free end thereof, one of the arms being provided with a roll adapted to coact with the cam projection on said 5 pulley and the other arm having a shouldered projection; a reciprocating rod adapted to be locked in its lowest position by said shouldered projection; means movable with said lug for lowering said rod; a brake for 10 said pulley; a cam for actuating said brake; clutch mechanism for controlling the operation of said cam; and means actuated by said rod for actuating said clutch mechanism.

15 49. In a device of the class described, the combination of a driving shaft; a pulley secured thereto having a cam projection revoluble therewith; a member loosely mounted to oscillate on said shaft; a device interposed 20 between said member and pulley for normally preventing the rotation of said pulley independently of said member; means for releasing said device from said pulley to permit its rotation; a pivoted lug for actuating 25 said releasing means provided with a peripheral cam; a member under the control of the operator for moving said pivoted lug about its pivot; a pivoted arm having a cam surface normally retained in contact 30 with said peripheral cam; a two armed lever pivoted to the free end thereof, one of the arms being provided with a roll adapted to coact with the cam projection on said pulley and the other arm having a shouldered projection; a reciprocating rod adapted to be 35 locked in its lowest position by said shouldered projection and having a lateral shoulder; means movable with said lug and provided with a radial shoulder adapted to co- 40 act with said lateral shoulder and effect a lowering of said rod; a brake for said pulley; a cam for actuating said brake; clutch mechanism for controlling the operation of said cam; and means actuated by said rod 45 for controlling said clutch mechanism.

50 50. In a device of the class described, the combination of a driving shaft; a pulley secured thereto; a member loosely mounted to oscillate on said shaft; a device interposed 55 between said member and pulley for normally preventing the rotation of said pulley independently of said member; means for releasing said device from said pulley to permit its rotation; a sheave adapted to be driven by the pulley driving member; a clutch member coacting therewith; a brake for said pulley actuated by said clutch member; and means under the control of the operator for simultaneously disengaging said 60 clutch member from said sheave and actuating said releasing means.

51. In a device of the class described, the combination of a driving shaft; a pulley secured thereto; a member loosely mounted 65 to oscillate on said shaft; a device inter-

posed between said member and pulley for normally preventing the rotation of said pulley independently of said member; means for releasing said device from said pulley to permit its rotation; a sheave adapted to be 70 driven by the pulley driving member; a clutch member coacting therewith; a brake for said pulley actuated by said clutch member; and means including a reciprocating rod under the control of the operator for 75 simultaneously disengaging said clutch member from said sheave and actuating said releasing means.

52. In a device of the class described, the combination of a driving shaft; a pulley secured thereto; a member loosely mounted to oscillate on said shaft; a device interposed between said member and pulley for normally preventing the rotation of said pulley independently of said member; means 80 for releasing said device from said pulley to permit its rotation; a sheave adapted to be driven by the pulley driving member; a clutch member coacting therewith; a brake for said pulley actuated by said clutch member; means including a reciprocating rod under the control of the operator for simultaneously 85 disengaging said clutch member from said sheave and actuating said releasing means; and a device for locking said 90 rod during the rotation of the driving shaft.

53. In a device of the class described, the combination of a driving shaft; a pulley secured thereto; a member loosely mounted to oscillate on said shaft; a device interposed 100 between said member and pulley for normally preventing the rotation of said pulley independently of said member; means for releasing said device from said pulley to permit its rotation; a sheave adapted to be 105 driven by the pulley driving member; a clutch member coacting therewith; a brake for said pulley; a cam rotatable with said clutch member and adapted to actuate said brake; and means under the control of the 110 operator for disengaging said clutch member from said sheave and simultaneously actuating said releasing means.

54. In a device of the class described, the combination of a driving shaft; a pulley secured thereto; a member loosely mounted to oscillate on said shaft; a device interposed 115 between said member and pulley for normally preventing the rotation of said pulley independently of said member; means for releasing said device from said pulley to permit its rotation; a sheave adapted to be driven by the pulley driving member; a clutch member coacting therewith; a brake for said pulley; a cam rotatable with said 120 clutch member and adapted to actuate said brake; means under the control of the operator for disengaging said clutch member from said sheave and simultaneously actuating 125 said releasing means; and means for 130

rotating said cam to its normal position when said clutch member has been disengaged from said sheave.

55. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a sheave adapted to be driven by the pulley driving member; a clutch member coacting therewith; a brake for said pulley; a cam rotatable with said clutch member and adapted to actuate said brake; means under the control of the operator for disengaging said clutch member from said sheave and simultaneously actuating said releasing means; a support on which said cam and clutch member are revolubly mounted; and a spring the ends of which are secured respectively to said clutch member and support whereby the cam is returned to its normal position when said clutch member has been disengaged from said sheave.

56. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a tubular support; a shaft therein adapted to be rotated and moved endwise; a sheave on the outer end thereof adapted to be driven by the pulley driving member; a clutch member mounted on said tubular support and adapted to engage said sheave and be driven thereby; a cam rotated by said clutch member; a brake for said pulley actuated by said cam; and means under the control of the operator for moving said sheave shaft endwise.

57. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a tubular support; a shaft therein adapted to be rotated and moved endwise; a sheave on the outer end thereof adapted to be driven by the pulley driving member; a clutch member mounted on said tubular support and adapted to engage said sheave and be driven thereby; a cam rotated by said clutch member; a brake for said pulley actuated by said cam; means under the control of the operator for moving said sheave shaft endwise; and means

interposed between said sheave and clutch member for rotating said cam to its normal position when said clutch member and sheave have been disengaged.

58. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a tubular support having a flange at its outer end; a shaft therein adapted to be rotated and moved endwise; a sheave on the outer end thereof adapted to be driven by the pulley driving member; a clutch member mounted on said tubular support between said flange and the frame of the machine and adapted to engage said sheave and be driven thereby; a cam rotated by said clutch member; a thrust bearing interposed between said frame and the inner end of said clutch member; a brake for said pulley actuated by said cam; and means under the control of the operator for moving said sheave shaft endwise.

59. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to permit its rotation; a tubular support; a shaft therein adapted to be rotated and moved endwise; a sheave on the outer end thereof adapted to be driven by the pulley driving member; a clutch member mounted on said tubular support and adapted to engage said sheave and be driven thereby; a cam rotated by said clutch member; a brake for said pulley actuated by said cam; means under the control of the operator for moving said sheave shaft endwise; a headed member in the inner end of said sheave shaft; a washer surrounding said headed member and bearing against an annular shoulder in the bore of said tubular support; a spring between said washer and the head of said headed member; and means under the control of the operator for forcing said headed member against the tension of said spring to disengage said sheave and clutch member.

60. In a device of the class described, the combination of a driving shaft; a pulley secured thereto; a member loosely mounted to oscillate on said shaft; a device interposed between said member and pulley for normally preventing the rotation of said pulley independently of said member; means for releasing said device from said pulley to per-

mit its rotation; a tubular support; a shaft therein adapted to be rotated and moved endwise; a sheave on the outer end thereof adapted to be driven by the pulley driving member; a clutch member mounted on said tubular support and adapted to engage said sheave and be driven thereby; a cam rotated by said clutch member; a brake for said pulley actuated by said cam; means under the control of the operator for moving said sheave shaft endwise; a headed member in the inner end of said sheave shaft; a washer surrounding said headed member and bearing against an annular shoulder in the bore of said tubular support; a spring between 15 said washer and the head of said headed member; a pivoted member having an arm bearing against said headed member; and means under the control of the operator for moving said pivoted member about its pivot. 20

Signed by us at Lynn, Mass., this 12th day of April, 1917.
